UNITED STATES PATENT OFFICE.

WILLIAM A. WYNANT, OF DEERTRAIL, COLORADO.

BEAN-HARVESTER.

1,275,640.

Specification of Letters Patent. Patented Aug. 13, 1918.

Application filed December 26, 1917. Serial No. 208,951.

To all whom it may concern:

Be it known that I, WILLIAM A. WYNANT, a citizen of the United States, residing at Deertrail, in the county of Arapahoe and State of Colorado, have invented certain new and useful Improvements in Bean-Harvesters, of which the following is a specification, reference being had to the accompanying drawings.

10 This invention relates to certain improvements in bean harvesters and it is an object of the invention to provide a novel and improved device of this general character including a digging or lifting implement discharging upon an elevator which in turn delivers upon a conveyer traveling transversely of the harvester and delivering at one side thereof.

Furthermore it is an object of the invention to provide a novel and improved device of this general character including an elevator and a conveyer together with means whereby the same are driven from a supporting axle.

25 The invention consists in the details of construction and in the combination and arrangement of the several parts of my improved bean harvester whereby certain important advantages are attained and the 30 device rendered simpler, less expensive and otherwise more convenient and advantageous for use, as will be hereinafter more fully set forth.

The novel features of my invention will 35 hereinafter be definitely claimed.

In order that my invention may be the better understood, I will now proceed to describe the same with reference to the accompanying drawings, wherein:

40 Figure 1 is a view in top plan of a harvester constructed in accordance with an embodiment of my invention;

Fig. 2 is a view partly in side elevation and partly in vertical section of my improved harvester, as herein disclosed;

45 Fig. 3 is a fragmentary sectional view taken through the upper end of the elevator and through the conveyer as herein employed; and

50 Fig. 4 is a fragmentary view partly in rear elevation and partly in section, of the upper end portion of the elevator and the adjacent portion of the conveyer.

As disclosed in the accompanying drawings 55 1 denotes an axle having loosely mounted upon the opposite end portions support-

ing wheels 2. The wheels 2 are provided with the spring pressed pawls 3 normally engaging the ratchets 4 fixed to the axle 1 whereby said axle 1 will be caused to rotate in unison with and in the same general direction as the wheels 2 upon the forward advance of the machine. Arranged between the supporting wheels 2 and mounted for rocking movement in a vertical direction 60 are the elevator frames F herein disclosed as two in number. Each of the frames F consists of the side boards 5 disposed on a predetermined downward incline toward the front end of the machine and the lower end 65 portions of the side boards 5 are provided with the upwardly and forwardly directed arcuate arms 6 having their forward or free end portions 7 in convergence and pivotally engaged as at 8 with an inwardly directed 70 arm 9 carried by the transversely disposed beam 10 arranged in advance of the frames F. The beam 10 is supported in a conventional manner by the caster wheels 11.

75 Pivotedly engaged with the inner end portion of each of the arms 9 is an upstanding link 12 having its upper end portion pivotally engaged with a rock arm 14 carried by a shaft 15 rotatably supported by the arms 6 of the adjacent frame F. Suitably fixed to the shaft 15 is an upstanding lever 16 provided with the latch mechanism 17 of a well-known type and which coacts with the upstanding rack 18 carried by one of the arms 6. The lever 16 is positioned in 80 such proximity to the seat structure S as to permit the same being readily manipulated by the occupant of the seat when it is desired to vertically adjust the lower end portion of the frame F.

95 Positioned between the lower end portions of the side boards 5 of each of the frames F is a digging implement or lifting member 19. The implement or member 19 is disposed on a predetermined incline and extends in advance of the side boards 5 and the extended portion thereof is substantially V-shaped with its apex outwardly directed.

100 Rotatably supported by the side boards 5 of each of the frames F in close proximity to and below the inner end of the digging implement or lifting member 19 is a shaft 20 provided adjacent the inner face of each of the side boards 5 with a sprocket wheel 21. Disposed around the sprocket 21 is the 105 chain 22 which is also directed around a sprocket 23 fixed to a shaft 24 rotatably sup-

ported by the upper or rear end portions of the side boards 5. The sprockets 21 and 24 are in longitudinal alinement.

The shaft 24 extends outwardly beyond the frame F and the outer end portion of said shaft 24 is mounted in the upper end portions of the elongated parallel members 25 which have their lower end portions operatively engaged with the extended portion 10 of the axle 1. The opposite or upper extremities of the members 25 are suitably engaged with the conveyer frame C, which will be hereinafter more particularly referred to. The shaft 24 intermediate the 15 members 25 has affixed thereto a sprocket 26 around which is imposed the chain 26' which is also directed around a sprocket 27 fixed to the shaft 28 rotatably supported by the members 25 adjacent the lower ends thereof. The shaft 28 has also affixed thereto a gear 29 in mesh with the gear 30 fixed to the axle 1, whereby it will be perceived that upon rotation of the gear 30 proper movement will be imparted to the chains 22. 20 The pair of chains 22 coacting with each of the frames F are connected by the cross bars 31 arranged in predetermined spaced relation and upon which the vines or the like lifted by the digging implement or lifting member 19 are discharged. Vines or 25 the like discharged upon the member 31 are carried upwardly of the frame F and during such travel the upper stretch of each of the chains 22 is caused to vibrate through the medium of a sprocket 32 whereby dirt or other loose matter carried by the vines is separated therefrom.

Supported by the upper or rear end portions of the side boards 5 of the frame F 30 is a conveyer frame C disposed transversely of the machine and extending beyond a side thereof and the extended portion of the frame C is formed with a buncher or discharge member D. 33 denotes an endless conveyer arranged at the bottom of the frame C and traveling at each end around a roller 34 rotatably supported by the frame C and disposed transversely thereof. The roller 34 remote from the buncher or discharge member D is provided with an extended shaft 35 and to the extended portion thereof is affixed a gear 36 in mesh with the

gear 37 rotatably supported by the adjacent end of the conveyer C. The outer face of the gear 37 is provided with a bevel gear 38 meshing with a similar gear 39 affixed to the extended portion of the shaft 24 whereby it will be perceived that upon the forward advance of my improved harvester the conveyer 33 will be caused to travel in the 60 desired manner.

The inner side wall of the frame C intermediate the side boards 5 of each of the frames F is cut out as indicated at 40 so that the cross members or bars 31 may readily discharge upon the conveyer 33.

From the foregoing description, it is thought to be obvious that a bean harvester constructed in accordance with my invention is particularly well adapted for use by reason of the convenience and facility with which it may be assembled and operated and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

A device of the character described comprising a wheel supported axle, a frame mounted thereon, a ground engaging element carried by one end of the frame, transversely disposed shafts carried by the opposite end portions of the frame, an endless conveyer disposed around said shafts, one of said shafts extending beyond the side of the frame, a member interposed between the extended portion of the shaft and the axle, a shaft supported by said member and operatively connected with the axle, and an operative connection between the shaft of the member and the extended portion of the shaft of the frame.

In testimony whereof I hereunto affix my signature in the presence of two witnesses.

WILLIAM A. WYNANT.

Witnesses:

F. J. SHINDLER,
S. A. Wood.
